UNITED STATES PATENT OFFICE.

ROBERT C. SCHEMML, OF UNION CITY, INDIANA, ASSIGNOR TO THE BACKSTAY MACHINE & LEATHER COMPANY, OF UNION CITY, INDIANA, A CORPORATION OF INDIANA.

BOW AND BOW COVER FOR VEHICLE TOPS.

Application filed November 25, 1922. Serial No. 603,379.

To all whom it may concern:

Be it known that I, ROBERT C. SCHEMML, a citizen of the United States, residing at Union City, in the county of Randolph and 5 State of Indiana, have invented certain new and useful Improvements in Bows and Bow Covers for Vehicle Tops; and I do hereby declare the following to be a full, clear, and exact description of the invention, such as 10 will enable others skilled in the art to which it appertains to make and use the same.

My invention relates to automobile and other vehicle tops, but more particularly to top-bows and covers for such bows used in 15 spreading and supporting vehicle tops. It has long been customary to cover these wooden bows with material corresponding, or at least harmonizing with the interior trim of the vehicle, various colors and grades 20 of cloth being employed for this purpose, as also leather and leather substitutes. Heretofore it has also been the practice either to seam, or to overlap covers upon the outer surface of bows, and if merely overlapped, 25 to secure the cover to its respective bow by a line of tacks. Whether seamed or tacked to the outer surface of bows, however, an obstruction is thus formed and interposed in 30 assemling, between these bows and the top of the vehicle, which obstruction in time wears and disfigures the top due to continuous vibrations, and particularly is this so 35 when tacks are employed as the means of securing bow covers in position.

As well understood by persons skilled in the building and trimming of vehicle tops, the spreading and supporting bows are of 40 varying cross sectional dimensions, and in addition the back bows are usually somewhat irregular in shape, but in all events these bows taper toward each end where they are in practice securely supported in the customary upstanding metallic tubular bow sockets.

From time to time there have been attempts made by trimmers to overcome the 45 objections aforesaid; it has been proposed to encase top bows in plastic material such as paper pulp; attempts have been made to 50 cover bows by means of cords wound, woven or braided permanently thereon; and covers of leather or other materials have been formed wrong side out and then turned outside in upon the particular bow for which 55 especially made and fitted. At the present

time it is not uncommon to form bow covers from fabric, and from imitation leather strips cut upon the bias to facilitate stretching same over the varying shapes of top bows, and to thereafter secure the overlapped edges of such stretched covers by means of tacks, and sometimes by stitching.

I am not aware however, of a single instance prior to my present invention, as hereinafter claimed, wherein a bow-cover has been produced comprising an enclosing tubular envelope having inherent resiliency, and a primarily uniform cross sectional diameter not greater than that of the smallest portion of the bow to be covered, whereby in assembling said bow and cover, the latter may be instantly drawn and stretched over the former, thus automatically adapting itself to varying dimensions or bow irregularities, and assuming its final operative position upon the bow irrespective of fastening means other than its inherent elasticity, irrespective of the material employed so long as it is sufficiently stretchable and possesses the other characteristics aforesaid, and regardless of whether the said tube is seamed or seamless.

My present invention has for an object to overcome practical objections to all of the forms of bow covers aforesaid, and to produce a novel and highly efficient cover for the purposes stated, comprising a seamless, tubular knitted structure which automatically adapts itself to irregular configurations, and which can be instantly applied without 90 the necessity of fastening means other than those inherent in the cover itself.

My invention further resides in the conception of this idea of means for neatly and quickly covering top-bows with a seamless 95 tubular knitted envelope, manufactured in continuous lengths and cut into sections of suitable length as applied.

The invention will be hereinafter particularly described, and then pointed out 100 in the claims following.

In the accompanying drawings which form part of this application for Letters Patent, and whereon corresponding numerals refer to like parts in the several views;

Figure 1 represents in perspective a portion of a top bow for automobiles, being in this instance the back bow, and provided with my improved form of bow cover extending down to, and slightly beyond the 110

point where received and supported in an ordinary bow socket (not shown);

Figure 2 is a transverse sectional view taken through the bow and tubular bow cover on the line 2-2 of Figure 1;

Figure 3 is also a transverse sectional view on the line 3-3 of Figure 1; and

Figure 4 represents a short section of my tubular bow cover in perspective.

Reference being had to the drawings and numerals thereon, 5 indicates a top bow for use in spreading and supporting automobile or other vehicle tops, in the ordinary manner. These bows are usually made of wood and have tapering ends 6, received in the usual metallic tubular supports or bow sockets rising from the body of the vehicle. They are also somewhat irregular in form being broadened and flattened at their upper intermediate portions 7 resulting in perceptible enlargements such as 8 at corresponding points upon opposite sides of the bow, and are shouldered as at 9 to limit the downward thrust of tapering ends 6 in the ordinary bow sockets (not shown).

The numeral 10 indicates my improved form of elastic tubular, knitted envelope or cover, comprising a multiplicity of interlocking loops or meshes, as best indicated by Figure 4 of the drawings. This article of manufacture is made in great lengths of any approved material, color or finish to harmonize with the interior of the vehicle top in which used, including imitation leather when desired, in which latter event a "welt-cloth" may be employed, which forms the subject-matter of a separate application for Letters Patent, filed by me simultaneously herewith.

In applying bow covers, constructed and arranged in substantial accordance with my conception of this invention, the seamless, tubular and elastic cover 10, of a cross sectional area not greater than that of the smallest portion of a bow to be covered, is quickly drawn over such bow at one end until it assumes substantially the position indicated by Figure 1 of the drawings, where it automatically accommodates itself to all irregularities, presenting at all points a snug and neat fit without the necessity of further fastening means, and absolutely without objectionable seams or lap joints. When so covered the bow 5 is introduced into the usual bow socket (not shown) which also houses the extreme ends of the cover 10 below shoulders 9, thereby contributing

to a neatness of finish, and at the same time cushioning said bow in its supporting sockets.

From the foregoing it is believed that the construction, operation and advantages of my invention will be readily understood and appreciated by persons skilled in the art to which it relates, and it is apparent that various structural changes may be made and substituted for those shown and described without in the least departing from the spirit of my invention as expressed in the claims following.

Having thus described my invention what I now claim and desire to secure by Letters Patent is:

1. A bow cover for vehicle tops comprising a tubular bow-enclosing envelope made of elastic textile fabric adapted to automatically conform to the varying transverse dimensions of the bow covered.

2. A bow cover for vehicle tops comprising a seamless tubular bow-enclosing envelope made of elastic textile fabric adapted to automatically conform to the varying transverse dimensions of the bow covered.

3. A bow cover for vehicle tops comprising a seamless knitted bow-enclosing envelope adapted to automatically conform to the varying transverse dimensions of the bow covered.

4. A bow for vehicle tops in combination with a tubular resilient bow-enclosing envelope of textile fabric, adapted to automatically conform to the varying transverse dimensions of said bow, and to be retained thereon in operative position by agency of its inherent resiliency.

5. A bow for vehicle tops in combination with a tubular enclosing envelope of textile fabric having inherent resiliency and a primarily uniform cross sectional diameter not greater than that of the smallest portion of the bow covered.

6. A bow for vehicle tops in combination with a tubular enclosing envelope having inherent resiliency, and a primarily uniform cross sectional diameter not greater than that of the smallest portion of the bow covered.

In testimony whereof I affix my signature, in presence of two subscribing witnesses.

ROBERT C. SCHÈMMEL.
